UNITED STATES PATENT OFFICE.

HERBERT AUSTIN, OF BROMSGROVE, ENGLAND.

BORING-BAR.

1,241,073.

Specification of Letters Patent. Patented Sept. 25, 1917.

Application filed August 21, 1916. Serial No. 116,011.

To all whom it may concern:

Be it known that I, HERBERT AUSTIN, a subject of the King of Great Britain, and residing at Bromsgrove, in the county of 5 Worcester, England, engineer, have invented certain new and useful Improvements in Boring-Bars, of which the following is a specification.

This invention relates to the type of boring bar in which a bar (hereinafter termed the "guide bar", when such is necessary to distinguish it from the complete boring bar), which passes through the interior which is to be bored, is surrounded by a 10 sleeve or the like which carries the cutting tool in a manner which allows the tool to move out in relation to the sleeve, the guide bar being formed with a surface which acts as a "former" and insures that as the sleeve 15 is moved endwise in relation to the guide bar the cutting edge of the tool will at any point of its travel be at the required distance from the axis of the boring bar to cut the interior which is being bored to the required diameter 20 at such point; and has for its object certain improvements therein.

According to this invention the tool is pivotally connected with the sleeve or the like, and in practice it is convenient to fix 30 the tool in a tool-holder and to pivot the tool-holder to the sleeve and though the tool or tool holder would necessarily press against the surface of the guide bar while the tool is cutting, it is pressed against such surface by 35 means of a spring to insure that it will be in proper position when it is being moved along to commence a cut and will remain in such position even though it may have to pass over a chambered portion of the interior 40 which it is used to bore; and, by the use of such spring it is insured that the tool will be prevented from wagging when the boring bar is being carried about.

If a boring bar, of the type defined in the 45 opening paragraph hereof, is intended to be used for boring an interior of comparatively small diameter, the portion of the guide bar along which the sleeve is slidable may be eccentric to the true axis of the complete 50 appliance, in which case, for the sake of strength, the sleeve also may be eccentric to such axis, but in the opposite direction to the eccentricity of such portion of the guide bar.

55 In order that the invention may be clearly understood, I will now describe a convenient

application of the same as applied, by way of example, to boring an explosive shell.

Of these drawings:

Figure 1 represents, mainly in sectional plan, a boring bar constructed according to this invention, in position within an explosive shell body.

Fig. 2 is a detached view of the boring bar as seen looking in the direction of the arrow, 65 Fig. 1.

Fig. 3 is a transverse section through the boring bar, taken in the plane indicated by line 3—3 of Fig. 1.

Fig. 4 is a transverse section through the 70 boring bar, taken in the plane indicated by line 4—4 of Fig. 2;

Fig. 5 shows, in side elevation, means of securing the forward end of the guide bar when the boring bar is in use, and 75

Fig. 6 represents an end elevation looking toward the right of Fig. 5.

A is the explosive shell. B is a guide bar forming one of the main members of the boring bar. C is a sleeve which is slidable 80 along the bar B. D is the tool-holder, and E the cutting tool. The shell A, bar B, and sleeve C, are shown to have a considerable portion of their rear ends broken away, for convenience of illustration. In this instance, 85 the bar being used to bore an interior of somewhat small diameter, the portion of the bar B along which the sleeve C is slidable is shown to be eccentric to the forward end B' of the bar which passes axially through 90 the forward end of the shell. In order to insure the necessary strength of the sleeve (which is arranged within the somewhat confined space shown) the sleeve also is made eccentric, but in the opposite direction to the 95 eccentricity of the portion B of the guide bar, as is clearly shown by Figs. 3 and 4. A key-way b is formed in the surface of the bar B, and a key b' of the sleeve C is slid- able within the key-way, whereby while the 100 sleeve can be moved endwise of the bar it cannot turn in relation thereto. Preferably, the guide bar B is fixed and the shell re- volves, whereby the conoidal portion of the shell may be turned while the interior of the 105 shell is being bored; but obviously, this is not essential, as the boring bar might revolve and the shell be fixed. For the sake of defi- niteness in description I will assume that the bar B is fixed. The tool-holder D is pivoted 110

by means of a pin c' between the sides of a slot c which is formed through the wall of

the forward end of the sleeve C. Along one side of the portion of the bar B along which the sleeve C is slidable is a surface b^2 , b^3 , of which the surface b^2 is parallel with the axis 5 of the bar and the surface b^3 is curved. The tool holder D has a nose d at its forward end which bears along the surface b^2 , b^3 , as the sleeve is moved forward along the bar B, and this surface b^2 , b^3 , acts as a "former" to 10 the tool-holder and insures that the tool will bore out the interior of the shell to the shape required, that is to say, parallel while the tool-holder is traveling along the surface b^2 and curved while it is traveling along the 15 surface b^3 . In the particular application illustrated, the surface b^2 is shown by Fig. 4 to be simply a flat cut along the side of the bar B, while the surface b^3 forms the bottom of a groove within the bar. In some cases, 20 however, it may be found preferable to form the surface b^2 as the bottom of a groove which will run into the groove of which the curved surface b^3 forms the bottom.

The shell passes through, and is held by, 25 a clutch which is revolved within a frame which is fixed upon the machine bed; in a known or any convenient manner; and the rear end of the sleeve is fixed to a saddle or the like which is slidable along the machine 30 bed and is moved therealong to give the required feed to the cutter. The forward end of the guide bar passes through a fixed support by which it is kept central and in relation to which it is prevented from moving 35 endwise, and is otherwise kept truly in place by the sleeve. The guide bar may be prevented from moving endwise in any suitable manner. Conveniently in the manner shown by Fig. 5, according to which notches 40 b^7 are cut in opposite sides of the bar, with the inner pair of which a key K, at the inner face of the support M, through which the bar passes, is engaged by passing opposite sides of the key through the notches, 45 and with the outer pair of which a key K', at the outer face of the support, is similarly engaged, the latter key being tapered at its outer face, as shown, to bear against slanted outer sides of the notches and thus draw the 50 bar endwise until the key K comes against the inner face of the support M. A hole in the underside of the sleeve may engage with a stud of the saddle, to insure that, when the boring bar has been removed and a fresh 55 shell has been put in place, the correct position of the saddle in relation to the sleeve will result from lowering the underside of the sleeve over the stud of the saddle. Conveniently, the rear end of the sleeve rests in 60 bearings of the saddle and is clamped down thereon, the stud aforesaid standing up within one of such bearings. A removable bush N, having a collar n at its inner end, and a removable bush N', having a collar n' 65 at its outer end, enable the forward end of

the bar to be readily passed through the support and its other end to be dropped into the bearings of the saddle.

The tool E is shown as fixed within the tool-holder by means of a screw F; and a 70 spring G is shown as fixed at one end to the tool-holder and bearing at its other end against the rear end of the tool, for the purpose of moving the tool outward somewhat when the screw F has been slackened back, 75 and thereby facilitating the removal of the tool from the holder. In order to insure that the forward end of the tool-holder will always bear upon the surface b^2 , b^3 , a spring H which is fixed at one end to the sleeve 80 bears against a heel of the tool-holder.

The key b, which is slidable within the key-way b of the bar B, is passed through a slotted opening which is formed through the wall of the sleeve, and besides fitting 85 tightly in such slot is fixed by screws b⁵ which pass through ears b⁴ which lie within shallow extensions of the slot, all as is well understood.

b⁶ is a channel for a lubricating tube.

The purpose of making the portion of the guide-bar along which the sleeve is slidable eccentric to the true axis of the complete appliance is to provide increased space for the tool-holder between the guide-bar and the 95 interior surface of the article which is being bored, and at the same time allow the guide-bar to be made of such strength that it will not be unduly weakened at the point where the "former" surface is cut in most deeply, 100 and allow the side of the sleeve where the slot is cut to receive the tool-holder to be made stronger than could otherwise be the case.

Having fully described my invention 105 what I claim and desire to secure by Letters Patent is:—

1. A boring bar comprising a guide bar having a "former" surface, a sleeve slidable on said guide bar and held against rotation thereon, and a boring means pivotally connected to said sleeve and guided by said "former" surface of said bar.

2. A boring bar comprising a guide bar having a "former" surface including a 115 straight portion parallel to the axis thereof and a curved portion continuous with said straight portion, a sleeve slidable on said guide bar and held against rotation thereon, and a boring means pivotally connected to 120 said sleeve and guided by said "former" surface of said bar.

3. A boring bar comprising a guide bar provided with a "former" surface, a sleeve slidable on said guide bar and held against 125 rotation thereon, a tool holder pivotally connected to said sleeve and guided by said "former" surface of said bar, and a boring tool carried by said tool holder.

4. A boring bar comprising a guide bar 130

having an eccentric body provided with a "former" surface, a sleeve slidable on said eccentric body and held against rotation thereon, and a boring means pivotally connected to said sleeve and guided on said "former" surface of said bar.

5. A boring bar comprising a guide bar having an eccentric body provided with a "former" surface, a sleeve slidable on said eccentric body and held against rotation thereon, said sleeve having an eccentricity in reverse of the eccentricity of said guide bar, and a boring means pivotally connected to said sleeve and guided on said "former" 10 face of said bar.

15. A boring bar for forming a tapered bore comprising a guide bar having a "former" surface, a sleeve slidable on said guide bar and held against rotation thereon, and a tool holder pivoted to said sleeve and provided at its forward end with a contact nose 20 adapted to engage said "former" surface,

a spring secured to said sleeve, engaging the rear end of said tool holder and operative to hold said nose in contact with said "former," and a boring tool carried by said tool holder.

25. 7. A boring bar comprising a guide bar having a "former" surface including a straight plane portion and a grooved portion continuous with said straight portion, a sleeve slidable on said guide bar and held against rotation thereon, and a boring means 30 pivotally connected to said sleeve and guided by said "former" surface of said bar.

35. In witness whereof I have hereunto signed my name this 4th day of August 1916, in the presence of two subscribing witnesses.

HERBERT AUSTIN.
